(57) **CLAIM**

The ornamental design for a bottle with pump head, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view of a bottle with pump head showing a first embodiment of our design including the specific colors shown;

FIG. 2 is a front view thereof;

FIG. 3 is a rear view thereof;

FIG. 4 is a right side view thereof;

FIG. 5 is a left side view thereof;

FIG. 6 is a top plan view thereof;

FIG. 7 is a bottom plan view thereof;

FIG. 8 is a perspective view of a bottle with pump head showing a second embodiment of our design including the specific colors shown;

FIG. 9 is a front view thereof;

FIG. 10 is a rear view thereof;

FIG. 11 is a right side view thereof;

FIG. 12 is a left side view thereof;

FIG. 13 is a top plan view thereof;

FIG. 14 is a bottom plan view thereof;

FIG. 15 is a perspective view of a bottle with pump head showing a third embodiment of our design including the specific colors shown;

FIG. 16 is a front view thereof;

FIG. 17 is a rear view thereof;

FIG. 18 is a right side view thereof;

FIG. 19 is a left side view thereof;

FIG. 20 is a top plan view thereof;

FIG. 21 is a bottom plan view thereof;

FIG. 22 is a perspective view of a bottle with pump head showing a fourth embodiment of our design including the specific colors shown;

FIG. 23 is a front view thereof;
FIG. 24 is a rear view thereof;
FIG. 25 is a right side view thereof;
FIG. 26 is a left side view thereof;
FIG. 27 is a top plan view thereof;
FIG. 28 is a bottom plan view thereof;
FIG. 29 is a perspective view of a bottle with pump head showing a fifth embodiment of our design including the specific colors shown;
FIG. 30 is a front view thereof;
FIG. 31 is a rear view thereof;
FIG. 32 is a right side view thereof;
FIG. 33 is a left side view thereof;
FIG. 34 is a top plan view thereof;
FIG. 35 is a bottom plan view thereof;
FIG. 36 is a perspective view of a bottle with pump head showing a sixth embodiment of our design including the specific colors shown;
FIG. 37 is a front view thereof;
FIG. 38 is a rear view thereof;
FIG. 39 is a right side view thereof;
FIG. 40 is a left side view thereof;
FIG. 41 is a top plan view thereof;
FIG. 42 is a bottom plan view thereof;
FIG. 43 is a perspective view of a bottle with pump head showing a seventh embodiment of our design including the specific colors shown;
FIG. 44 is a front view thereof;
FIG. 45 is a rear view thereof;
FIG. 46 is a right side view thereof;
FIG. 47 is a left side view thereof;
FIG. 48 is a top plan view thereof;
FIG. 49 is a bottom plan view thereof;
FIG. 50 is a perspective view of a bottle with pump head showing an eighth embodiment of our design including the specific colors shown;
FIG. 51 is a front view thereof;
FIG. 52 is a rear view thereof;
FIG. 53 is a right side view thereof;
FIG. 54 is a left side view thereof;
FIG. 55 is a top plan view thereof;
FIG. 56 is a bottom plan view thereof;
FIG. 57 is a perspective view of a bottle with pump head showing a ninth embodiment of our design including the specific colors shown;
FIG. 58 is a front view thereof;
FIG. 59 is a rear view thereof;
FIG. 60 is a right side view thereof;
FIG. 61 is a left side view thereof;
FIG. 62 is a top plan view thereof;
FIG. 63 is a bottom plan view thereof;
FIG. 64 is a perspective view of a bottle with pump head showing a tenth embodiment of our design including the specific colors shown;
FIG. 65 is a front view thereof;
FIG. 66 is a rear view thereof;
FIG. 67 is a right side view thereof;
FIG. 68 is a left side view thereof;
FIG. 69 is a top plan view thereof;
FIG. 70 is a bottom plan view thereof;
FIG. 71 is a perspective view of a bottle with pump head showing an eleventh embodiment of our design including the specific colors shown;
FIG. 72 is a front view thereof;
FIG. 73 is a rear view thereof;

FIG. 74 is a right side view thereof;
FIG. 75 is a left side view thereof;
FIG. 76 is a top plan view thereof;
FIG. 77 is a bottom plan view thereof;
FIG. 78 is a perspective view of a bottle with pump head showing a twelfth embodiment of our design including the specific colors shown;
FIG. 79 is a front view thereof;
FIG. 80 is a rear view thereof;
FIG. 81 is a right side view thereof;
FIG. 82 is a left side view thereof;
FIG. 83 is a top plan view thereof;
FIG. 84 is a bottom plan view thereof;
FIG. 85 is a perspective view of a bottle with pump head showing a thirteenth embodiment of our design including the specific colors shown;
FIG. 86 is a front view thereof;
FIG. 87 is a rear view thereof;
FIG. 88 is a right side view thereof;
FIG. 89 is a left side view thereof;
FIG. 90 is a top plan view thereof;
FIG. 91 is a bottom plan view thereof;
FIG. 92 is a perspective view of a bottle with pump head showing a fourteenth embodiment of our design including the specific colors shown;
FIG. 93 is a front view thereof;
FIG. 94 is a rear view thereof;
FIG. 95 is a right side view thereof;
FIG. 96 is a left side view thereof;
FIG. 97 is a top plan view thereof;
FIG. 98 is a bottom plan view thereof;
FIG. 99 is a perspective view of a bottle with pump head showing a fifteenth embodiment of our design including the specific colors shown;
FIG. 100 is a front view thereof;
FIG. 101 is a rear view thereof;
FIG. 102 is a right side view thereof;
FIG. 103 is a left side view thereof;
FIG. 104 is a top plan view thereof;
FIG. 105 is a bottom plan view thereof;
FIG. 106 is a perspective view of a bottle with pump head showing a sixteenth embodiment of our design including the specific colors shown;
FIG. 107 is a front view thereof;
FIG. 108 is a rear view thereof;
FIG. 109 is a right side view thereof;
FIG. 110 is a left side view thereof;
FIG. 111 is a top plan view thereof;
FIG. 112 is a bottom plan view thereof;
FIG. 113 is a perspective view of a bottle with pump head showing a seventeenth embodiment of our design including the specific colors shown;
FIG. 114 is a front view thereof;
FIG. 115 is a rear view thereof;
FIG. 116 is a right side view thereof;
FIG. 117 is a left side view thereof;
FIG. 118 is a top plan view thereof;
FIG. 119 is a bottom plan view thereof;
FIG. 120 is a perspective view of a bottle with pump head showing an eighteenth embodiment of our design including the specific colors shown;
FIG. 121 is a front view thereof;
FIG. 122 is a rear view thereof;
FIG. 123 is a right side view thereof;
FIG. 124 is a left side view thereof;

FIG. 125 is a top plan view thereof;
 FIG. 126 is a bottom plan view thereof;
 FIG. 127 is a perspective view of a bottle with pump head showing a nineteenth embodiment of our design including the specific colors shown;
 FIG. 128 is a front view thereof;
 FIG. 129 is a rear view thereof;
 FIG. 130 is a right side view thereof;
 FIG. 131 is a left side view thereof;
 FIG. 132 is a top plan view thereof;
 FIG. 133 is a bottom plan view thereof;
 FIG. 134 is a perspective view of a bottle with pump head showing a twentieth embodiment of our design including the specific colors shown;
 FIG. 135 is a front view thereof;
 FIG. 136 is a rear view thereof;
 FIG. 137 is a right side view thereof;
 FIG. 138 is a left side view thereof;
 FIG. 139 is a top plan view thereof;
 FIG. 140 is a bottom plan view thereof;
 FIG. 141 is a perspective view of a bottle with pump head showing a twenty-first embodiment of our design including the specific colors shown;
 FIG. 142 is a front view thereof;
 FIG. 143 is a rear view thereof;
 FIG. 144 is a right side view thereof;
 FIG. 145 is a left side view thereof;
 FIG. 146 is a top plan view thereof;
 FIG. 147 is a bottom plan view thereof;
 FIG. 148 is a perspective view of a bottle with pump head showing a twenty-second embodiment of our design including the specific colors shown;
 FIG. 149 is a front view thereof;
 FIG. 150 is a rear view thereof;
 FIG. 151 is a right side view thereof;
 FIG. 152 is a left side view thereof;
 FIG. 153 is a top plan view thereof; and,
 FIG. 154 is a bottom plan view thereof.

The broken shown illustrate portions of the bottle with pump head that form no part of the claimed design.
